UNITED STATES PATENT OFFICE.

HERMANN WELCH, OF OSCEOLA, NEBRASKA.

PUMP.

SPECIFICATION forming part of Letters Patent No. 660,136, dated October 23, 1900.

Application filed January 16, 1900. Serial No. 1,669. (No model.)

To all whom it may concern:

Be it known that I, HERMANN WELCH, (whose post-office address is Osceola, Nebraska,) a citizen of the United States, residing at Osceola, in the county of Polk and State of Nebraska, have invented certain new and useful Improvements in Pumps; and I do hereby declare the following to be a full, clear, and exact description of the invention, such as will enable others skilled in the art to which it appertains to make and use the same.

My invention relates to improvements in pumps for use in deep wells; and the main object of the invention is to produce a pump of very simple construction which will be very effective in its operation, wherein all the work of lifting the water is done on the downstroke of the piston and no water is lifted on the upstroke thereof, and wherein the weight of the operating parts assists in raising the water, and water will be drawn into the cylinder as water is forced out at a suitable discharge or surface pipe.

The invention consists in certain novel constructions, combinations, and arrangements of parts, as will be hereinafter described and claimed.

In the accompanying drawings, Figure 1 is a vertical longitudinal section through my improved pump, the central portion being broken out to shorten the figure. Fig. 2 is a view, partly in section and partly in elevation, showing the pump arranged for use as a force-pump, the same parts being broken out; and Fig. 3 is a detail view showing a modified form of the piston and of the means of converting the pump into a force-pump.

A in the drawings represents a cylinder which is closed at its bottom and top, in which works a piston-rod B, which is hollow and carries a piston C, which closely fits the said cylinder. The top or head of the cylinder may be provided with a stuffing-box, through which the piston-rod works. The piston C is provided with a downwardly-opening valve or valves c. The hollow piston-rod B extends above the level of the pump-platform a suitable distance and has connected to it a suitable handle C' for raising and lowering the same. A spring, as D, surrounds the piston-rod and is interposed between a collar b, provided on said rod and the pump-platform, so

as to support said rod and assist in raising the same on its upstroke, the water only being raised on the downstroke. The piston-rod B operates above the cylinder in the outer casing E, which surrounds the same and which casing is provided with a discharge-spout e. The said casing E is preferably made in sections, the lower section being 55 threaded or otherwise secured into the collar e', secured to the under side of the pump-platform and the upper section of said casing secured in a similar collar e², secured to the upper surface of the pump-platform. A 60 discharge-pipe F extends from the lower end of the pump-cylinder A, on the outside of said cylinder, to a point in the outer casing E, as at e³, by means of which pipe F water is forced into said casing E on the downstroke 65 of the piston, as shown in Fig. 1. The discharge-pipe F may be provided with a valve f, which is opened as the piston descends, so that the water may be forced into said pipe and is automatically closed as the piston is 70 raised, so as to support the column of water contained in said pipe. A supply or section pipe G extends from a point near the upper end of the cylinder and on the outside thereof into the water in the well or cistern and is 75 provided with an upwardly-opening valve g, which valve as the piston descends admits water into the cylinder above the valves c, which valves are closed as the piston descends. The valve g in the supply-pipe G is closed as 80 the piston ascends and the valves c are opened, so that the water which was admitted into the piston above the valves c will be permitted to pass through the ports in the piston into that part of the cylinder below the 85 piston, and as the piston again descends, the valves c being closed, the water below the piston will be forced into the hollow piston-rod E and also out through the supply-pipe F. 90

The construction of the pump as thus far described is, it will be observed, a single-acting pump, which does all its work of lifting water on the downstroke of the piston and rod, and no water is lifted on the upstroke thereof, and I regard this as an important 95 feature of my invention, and I maintain this principle throughout all the constructions illustrated in the drawings and which will be hereinafter described.

To convert the pump into a force-pump, it is simply necessary to close the upper end of the hollow piston-rod and disconnect the same from the discharge-spout, as shown in Fig. 2, 5 and employ only the discharge-pipe F' as the means of discharging water from the cylinder, said pipe being extended above the pump-platform and made with or connected to a spout F². In said Fig. 2 the upper end of the 10 hollow piston-rod is closed by means of a cap I, which also serves as the upper bearing of the spring D. The same result can be accomplished by providing a plug J in the hollow piston-rod, as clearly shown in Fig. 3. It 15 will be observed that the weight of the rod and piston in descending, which is considerable, will assist in raising the water, and that on the upstroke of the rod no water whatever is lifted, and the lifting of the weight of the 20 rod and piston is greatly facilitated by the spring D.

In Fig. 3 of the drawings I have shown a slightly-modified construction as to the location of the valves in that the valves for admitting water into the cylinder are located in the piston-rod, as at c' c', instead of in the piston. The operation of the valves is precisely the same as in Figs. 1 and 2. The valves c' c' open downwardly, and as the piston and rod 25 descend the valves are closed, and as the piston and rod ascend the valves are opened and water is admitted through the same into the lower part of the cylinder beneath the piston.

Being simple in its construction and operation and no complicated parts being employed, there is little liability of the pump getting out of order, and when necessary repairs can be readily made.

From the foregoing it will be seen that I 40 have provided a combination-pump, which can be worked as a force-pump or not, as the convenience of the operator or the exigencies of the case may require. The pump combines compactness, rigidity, and great lifting, 45 capacity for the amount of energy expended in operating the same.

Having now described my invention, what I claim as new, and desire to secure by Letters Patent, is—

- 50 1. A pump, comprising in its construction a suitable cylinder closed at its bottom and top and located above the water in the bottom of the well, said cylinder being provided with an aperture at or near its top for the inlet of water, a hollow piston-rod carrying a solid piston disk or head which works in said cylinder, said piston-rod being also open at the bottom so that no water will be caught therein and required to be lifted on the upstroke 55 thereof, one or more suitable valves provided in said piston-rod or piston, a suction-pipe provided with an upwardly-opening valve, said valve in the suction-pipe, when closed, supporting a column of water above it, the 60 construction and arrangement being such that upon the descent of the piston, the valve or valves in said piston or rod will be closed

and the valve in the section-pipe opened and the water in the section below the piston forced into the piston-rod, and when the piston rises, the valve or valves in said piston or rod will be opened and the valve in the suction-pipe closed, and water will be admitted below the piston through the valve in said piston or rod, whereby no water will be 70 lifted or forced upwardly on the upstroke of the piston, and water will be raised on the downstroke only, the weight of the piston and rod assisting in raising the water, substantially as described.

2. A pump, comprising a cylinder closed at top and bottom and provided with an opening at or near its upper end for the admission of water, means for fixedly supporting the said cylinder above the water in the well, a hollow piston-rod adapted to work in said cylinder the full length thereof and which is always open at the bottom so that no water will be held in the piston-rod and required to be lifted on the upstroke thereof, said rod being 85 provided on its lower end with a piston, outwardly-opening valves hinged to the said piston, said valves being adapted to close the openings in the said piston upon the downstroke of the piston, and to be opened upon the upstroke thereof, a suction-pipe entering the opening in the side of the cylinder, provided with an upwardly-opening valve which opens as the piston descends and closes as it rises, and supports a column of water above it, a stuffing-box secured in the head of the cylinder, said stuffing-box being provided with an opening through which the piston-rod passes, a collar on said piston-rod, a handle connected to the piston-rod, and a spring 90 interposed between the collar and the pump-platform, the construction being such that no water will be lifted on the upstroke but only on the downstroke, and the water-lifting operation will be assisted by the weight of 95 the piston and rod, substantially as described.

3. A pump, comprising in its construction a suitable cylinder closed at its bottom and top and located above the water in the bottom of the well, said cylinder being provided with 100 an aperture at or near its top for the inlet of water, a hollow piston-rod carrying a solid piston disk or head which works in said cylinder, said piston-rod being also open at the bottom so that no water will be caught therein 105 and required to be lifted on the upstroke thereof, one or more suitable valves provided in said piston-rod or piston, a casing or pipe surrounding the hollow piston-rod above the cylinder and provided with a spout, a suction-pipe provided with an upwardly-opening valve, said valve in the suction-pipe, when closed, supporting a column of water above it, a discharge-pipe outside the cylinder leading from the lower end of the cylinder to the 115 casing of the hollow piston-rod above the cylinder, the construction and arrangement being such that upon the descent of the piston, the valve or valves in said piston or rod will 120

be closed and the valve in the suction-pipe opened and the water in the section below the piston forced into the piston-rod and discharge-pipe, and, when the piston rises, the
5 valve or valves in said piston or rod will be opened and the valve in the suction-pipe closed, and water will be admitted below the piston through the valve in said piston or rod, whereby no water will be lifted or forced
10 upwardly on the upstroke of the piston, and

water will be raised on the downstroke only, the weight of the piston and rod assisting in raising the water, substantially as described.

In testimony whereof I hereunto affix my signature in presence of two witnesses.

HERMANN WELCH.
